CLOCK RADIO

Robert D. Budlong, Skokie, Ill., assignor to Zenith
Radio Corporation, a corporation of Illinois

Application April 19, 1952, Serial No. 19,404

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Clock Radio, of which the following is a specification, reference being made to the accompanying drawing, forming a part thereof.

The single figure is a perspective view of a clock radio, showing my new design.

The design of the side of the radio not shown is similar to the design of the side shown. The design of the rear portion, not shown, is open.

I claim:

The ornamental design for a clock radio, as shown and described.

ROBERT D. BUDLONG.
